COIN CONTROLLED LOCK

Claude R. Thomas, Youngstown, Ohio, assignor
to Universal Manufacturing Company, Inc.,
Youngstown, Ohio, a corporation of Ohio

Application November 6, 1937, Serial No. 173,207

5 Claims. (Cl. 194—83)

The present invention relates to check or coin controlled locks particularly adapted for, although not necessarily limited to, use on doors of public toilet rooms and the like, to which admission may be had only upon the payment or deposit of a check or coin of predetermined character or denomination.

An object of the present invention is the provision of a novel lock of the character referred to, which will be simple in construction, reliable in operation, easy to assemble, and inexpensive to manufacture.

Another object of the present invention is the provision of a novel keeper for the bolt or a lock of the character referred to which keeper is applicable to different types of doors and can be used with door jambs of various thicknesses.

Another object of the present invention is the provision of a novel lock of the character referred to, provided with a bolt, the projecting part of which is of substantially uniform cross section and which bolt because of its shape cannot be withdrawn from its keeper by inserting an instrument between the lock case and the keeper.

Another object of the present invention is the provision of a novel bolt particularly adapted for use with locks of the character referred to, having the portion thereof which is adapted to normally project from the lock case of substantially uniform cross section.

Another object of the present invention is the provision of a novel, simple, and inexpensive lock of the character referred to, so constructed and arranged that it can be readily converted for use with different types of doors; with doors which swing in as well as those which swing out; and doors hinged either at the right hand or the left hand side.

The present invention resides in certain details of construction and combinations and arrangements of parts, and further objects and advantages thereof will be apparent to those skilled in the art to which the invention relates from the following description of the preferred embodiments thereof described with reference to the accompanying drawings forming a part of this specification, in which similar reference characters designate corresponding parts throughout the several views, and in which:

Fig. 1 is a front elevation of a lock embodying the present invention as applied to a left hand door that opens inwardly and a narrow jamb, a fragmentary part only of the door and jamb being shown;

Fig. 2 is a section with portions in elevation on the line 2—2 of Fig. 1;

Fig. 3 is a section with portions in elevation on the line 3—3 of Fig. 2;

5 Fig. 4 is an enlarged view of the door jamb and keeper shown in Figs. 1 and 3, approximately on the line 4—4 of Fig. 1;

Fig. 5 is a rear elevation of the lock case removed from the door showing the various elements of the lock in their normal positions;

10 Fig. 6 is a view similar to Fig. 5, but showing the bolt withdrawn through the medium of the coin control;

Fig. 7 is a view similar to Figs. 5 and 6, but 15 showing the various elements of the lock in a different operating position;

Fig. 8 is a view similar to Fig. 5 with portions 20 of the operating mechanism removed and broken away, so as to show certain other elements to better advantage;

Fig. 9 is a perspective view of the bolt shown 25 in Figs. 1 to 7 inclusive;

Fig. 10 is a view similar to Fig. 1 but showing 30 the lock as applied to a left hand door that opens inwardly and a wide jamb;

Fig. 11 is an enlarged view of the door jamb and keeper shown in Fig. 10 approximately on the line 11—11 of Fig. 10;

Fig. 12 is a view similar to Fig. 1, but showing 35 the lock as applied to a left hand door that opens outwardly and a narrow jamb; and,

Fig. 13 is an enlarged view of the door and keeper shown in Fig. 12, approximately on the line 13—13 of Fig. 12.

40 Although the invention is susceptible of various modifications and alternative constructions, it is herein illustrated and described in Figs. 1 to 9 inclusive as embodied in a lock applied to a left hand door that opens inwardly and cooperates with a thin door jamb.

Referring to the drawings the lock shown 45 therein comprises a main case or housing A, connected to a back plate B, mounted on the outside of a door designated generally by the reference character 11. The main case or housing A encloses the lock mechanism proper including the bolt C, is open at the back, and fits over the back plate B to which it is removably attached in a convenient manner. As shown, the upper end 50 of the back plate B has a pair of lugs 12 formed integral therewith, which engage within suitable apertures 13 formed in the inside of the top of the case A, and the lower end of the case A is provided with a screw 14 adapted to be threaded 55 into a suitably tapped aperture in the lower end

of the back plate B. The construction is such that the screw 14 can be rotated only through the medium of a cylinder lock 15 of conventional construction fixed to the front part of the case A. The lower part of the case A forms a coin or check receptacle, and the lock 15 prevents access thereto as well as to the lock mechanism proper, by unauthorized persons.

The combination keeper and stop shown comprises a member 16 having a rectangular aperture 29 formed in the face thereof adapted to receive the end of the bolt C, an inclined surface 21 leading up to the aperture 20, which inclined surfaces serves the usual purpose of forcing the bolt back into the lock case as the door is closed, and a ledge or projection 22 on the opposite side of the aperture 20 from the inclined surface 21 extending or projecting slightly to the left, as viewed in Figs. 1 and 3. The member 16 is also provided with suitable apertures both above and below the aperture 20 and the inclined surface 21 for the reception of rubber stops or bumpers 23 adapted to be secured therein in a manner hereinafter referred to. While the member 16 may be so constructed that it can be directly secured to the door jamb 24, as shown, it is connected to an angular member 25 which in turn is secured to the door jamb. The part 26 of the member 25 which extends normal to the jamb has a slot or groove formed therein, within which groove the member 16 is located. Flanges 27 on the member 26 project over or in front of a portion of the stops or bumpers 23 and limit the movement of the member 16 relative to the member 25 towards the left, as viewed in Fig. 4, by the engagement therewith of ledges 28 on the member 16. The ledges 28 project slightly forward of the rubber stops 23.

The member 16 is adapted to be integrally secured to the member 25 by screws 29 extending through holes in the part 26 of the member 25 and threaded into suitable tapped apertures in the member 16. The holes in the member 25 may be drilled at the time the lock is installed and their location determined by moving the member 16 relative to the member 25 until the desired final position is attained, depending upon the thickness of the door, and the thickness of the jamb, etc. The screws 29 threaded into the member 16 are slightly elongated so that, when they are in their final position, the ends thereof project slightly into the rubber stops or bumpers 23, thus retaining the same securely in position.

As shown, the bolt C is of rectangular cross-section and is slidably supported within a groove 34 in a member 35, within which groove it is retained by a plate 37 fixed to the member 35 by screws 38. The screws 38 are also employed to hold the member 35 in position on suitable pads 39 formed integral with the case A. The bolt C is continuously urged towards the left, as viewed in Figs. 5, 6 and 7, that is, in a direction to project the forward end thereof out of the lock case A by a coil spring 40, one end of which is secured to a projection 41 formed integral with the plate 37, while the other end thereof is secured to a pin 42 fixed to the bolt C and projecting forwardly therefrom, as viewed in Fig. 5, through a slot 44 formed in the plate 37. As previously stated, one of the objects of the invention is to provide a lock which can be readily adapted to either right or left hand doors, and, in regard to this matter, attention is called to the fact that by merely changing the hole in the lock case through which the end of the bolt C projects to

the opposite side of the case, the bolt assembly, including the bolt C, the member 35, and the plate 33, etc., can be rotated as a unit to provide a right hand lock.

5 The bolt C, in addition to being retracted, as the door is closed, by the engagement of the projecting end thereof with the inclined surface 21 of the keeper, may be retracted by any one of the following means: An outside knob or handle 45; an inside knob or handle 46; or a "key control." The outside knob 45 is connected to the bolt C through the medium of a "coin control," and, in the absence of a key, through the medium of which the "key control" may be operated, 10 the door can be opened from the outside only upon the deposit or insertion of a check or coin of suitable character or denomination.

In the preferred embodiment of the invention shown, the "coin control" comprises a disk-like 20 assembly, hereinafter designated the coin carrier, including two spaced plates 47 and 48 connected together by screws 49 and retained in predetermined spaced relation by a member 50 interposed therebetween and held in fixed relation 25 with reference thereto by the screws 49 previously referred to. The coin carrier also includes a member 51 pivotally supported between the disk-like members 47 and 48 by a screw 52. The member 51 normally hangs in a generally vertical position due to gravity, although it is to be understood that suitable spring means may be provided for this purpose, if desired. The members 50 and 51 are so constructed and arranged that with the members 47 and 48 they form a 30 chute 53 for the reception and guidance of a suitable coin or check X for operating the "coin control."

The member 51 is pivoted about midway between its ends to the disks 47 and 48 and a little 40 to one side of the center about which the coin carrier is rotatably supported. Slightly below the pivot 52 and on the side adjacent the member 50, the member 51 has formed thereon a seat or semi-circular recess 54 which cooperates with 45 the lower end of the member 50 to normally retain a coin or check of suitable denomination or character in the lower end of the chute 53. Under normal conditions, rotation of the member 51 in a counterclockwise direction, as viewed in Figs. 5 and 8, is prevented by the engagement of the upper end 55 of the member 51 against a combination coin or check chute and shutter member 56 slidably supported on a rod 57 fixed in the upper end of the lock case A, and by the 55 engagement of the lower end 60 of the same member 51 against a pin 61 (see Fig. 2) projecting from the rear of the bolt C, as viewed in Fig. 5 and extending through a slot or opening in the rear of the member 35 which permits free 60 movement of the pin 61 with the bolt.

The disk member 47 of the coin carrier assembly is fixed to the inner end of what might be called the hub of the outside knob 45 which hub projects into the interior of the lock case through a boss or member 64 and an opening in the front of the case. The member 64 is fastened to the front of the lock case by screws 65 and forms a bearing for the outside knob 45. The inner end or hub of the outside knob 45 is of reduced diameter and forms a shoulder adapted to engage the member 64. This shoulder together with the plate 47 of the coin carrier secures the knob against movement longitudinally of its axis of rotation.

70 Rotation of the coin carrier through the medi-

um of the outside knob 45 is limited by a pair of projections 66 and 67 formed integral with the member 50 and adapted to engage opposite sides of a raised pad 68 formed on the inside of the lock case A. A coil spring 70 operatively connected to a projection 71 on a plate 72 and to the upper of the two screws 49 continuously urges the projection 67 on the coin carrier into contact with the lower side of the pad 68. When the coin carrier is in this position the upper end of the coin chute 53 therein aligns with the lower end of a coin chute 75 in the combination chute and shutter member 56 previously referred to, when the latter is in its normal position as shown in Figs. 5 and 8. The upper end of the coin chute 75 in the member 56 is normally positioned directly underneath a check or coin slot 76 formed in the upper end of the lock case A. The construction is such that under normal conditions, that is, with the parts in the positions shown in Figs. 5 and 8, a coin or check of proper denomination or character inserted in the slot 76 will drop through the chutes 75 and 53 and come to rest in the position shown in the drawings.

Rotation of the coin carrier through the medium of the outside handle 45 with a coin in the position shown, will cause the member 51 to rotate with the coin carrier, as a unit, thus withdrawing the bolt C through the engagement of the lower end 60 of the member 51 with the pin 61 carried by the bolt. In the absence of a coin properly positioned in the carrier the member 51 will rotate freely about its pivot 52 upon rotation of the coin carrier, without having any effect whatsoever on the bolt. With a coin or check properly positioned in the coin carrier the outside knob, which is then operatively connected to the bolt through what has been termed the "coin control," can be operated in any desired manner to retract the bolt C any number of times, until the bolt is retracted by one of the other means provided for retracting the same.

When the bolt C is retracted with a coin or check in position by any of the provided means other than by the outside knob, such as by the projecting end of the bolt C striking against the inclined surface 21 of the keeper 15, as is the case when the door closes behind a person entering therethrough, the pin 61 is withdrawn from engagement with the lower end 60 of the member 51. This allows the member 51 to rotate about its pivot 52 in a counterclockwise direction, as viewed in Fig. 5, either under the weight of the coin or under the influence of gravity, assuming that the free rotation of the member 51 in the direction mentioned is not obstructed by the engagement of the upper end 53 with the shutter member 56 which, under the circumstances stated, would be the case, thus permitting the coin to drop into the bottom of the case A. If desired, the member 51 may be continuously urged in a counterclockwise direction about its pivot 52 by a comparatively light spring if the construction of the member is such that the action of gravity and the weight of the coin is not sufficient to produce the desired movement to release the coin or check.

In order to prevent the insertion of a second coin before the mechanism has been "reset" in a manner hereinafter referred to, provision is made for closing the coin slot 76 in the case A by the combination chute and shutter member 56, previously referred to, upon actuation of the bolt C through the medium of the "coin control" and

the outside knob. As previously stated the member 56 is slidably supported on the rod 57 fixed in the upper part of the lock case A. The member 56 is slidably supported on the rod 57 through the medium of a pair of projections 77 formed integral therewith, and the rod 57 projects through suitably aligned apertures formed in a pair of projections 78 formed by bending portions of the plate 72 at an angle to the main portion thereof. The shutter member 56 is continuously urged towards the right, as viewed in Fig. 5, by a coil spring 79 connected to a projection 80 on the plate 72 and to a pin 81 carried by the shutter 56 and projecting forwardly therefrom, as viewed in Fig. 5, through a slot 82 in the plate 72. Movement of the member 56 towards the right, as viewed in Fig. 5, under the action of the spring 79, is limited by a short tubular member 83 surrounding the rod 57 and positioned between the member 56 and the right hand projection 78.

The upper end 55 of the member 51 is so arranged that normally it engages the right hand side of the member 56 and upon rotation of the coin carrier with a coin properly positioned therein, moves the member 56 to the left against the action of the spring 79 to close the slot 76. In order to retain the shutter or closure member 56 in a position to maintain the coin slot 76 in the case A closed, after the outside knob has been released subsequent to the withdrawal of the bolt thereby, a bell crank lever-like spring-loaded pawl or detent 84 is provided. The pawl 84 is pivotally supported about a screw 88 threaded into the plate 72 and the horizontal arm 85 thereof has a shoulder 86 thereon adapted to engage behind the pin 81 as the shutter 56 approaches its extreme left hand position, see Fig. 6. The pawl 84 is adapted to be rotated in a clockwise direction, as viewed in Fig. 5, to "reset" the shutter, that is, to release the pin 81 from the shoulder 86 of the pawl thus permitting the shutter to return to its original position under the action of the spring 79, upon retraction of the bolt C, through the medium of either the inside handle 46 or the "key control" as will be hereinafter explained. The plate 72 previously referred to is detachably connected to suitable pads 90 formed in the upper corners of the lock case A, and in addition to performing the functions already referred to assists in supporting and guiding the shutter 56.

In order to provide visual means for indicating whether the room is occupied or vacant the front 55 of the lock case A is provided with a slot 92, see Fig. 1, through which suitable notations, such as "open" and "in use" carried by the shutter member 56 are visual, depending on whether the shutter is in its normal and inoperative position, that is, its right hand position as viewed in Fig. 5, or in a position to close the slot 76, which is the left hand position shown in Fig. 7.

The inside handle or knob 46 is operatively connected to a short shaft 93 by being driven onto the reduced upper end 94 thereof, as viewed in Fig. 3. A boss-like member 95 interposed between the shoulder formed by the reduced end of the shaft 93 and the handle or knob 46 forms a bearing for the shaft 93 and in turn for the inside knob 46. The member 95 is adapted to be secured to the door 11 by a pair of bosses 96 formed integral therewith which bosses project into suitable apertures in the door, and by screws 97 extending through the door from the outside thereof and threaded into suitably tapped

apertures in the bosses 96. The outer end of the shaft 93 has a tongue and groove connection with a member 100 rotatably supported in the plate 48 of the coin carrier and a plate 101 extending across the lock case and secured by screws 102 to suitable pads 68 formed on the inside of the lock case. The member 100 comprises a downwardly extending lever 105 the lower end of which is adapted to engage a pin 106 carried by the bolt C and projecting forwardly through the slot 44, as viewed in Fig. 5. The construction is such that upon rotation of the member 100 in a counterclockwise direction, as viewed in Fig. 5, the lever 105 cooperates with the pin 106 to retract the bolt C. A stop in the form of a pin 107 fixed in the plate 37 provides means for limiting the rotation of the lever 105 and in turn the member 100 in the reverse direction.

In addition to the lever 105, the member 100 comprises a pair of upwardly extending arms 108 and 109 the right hand one of which is adapted to engage a flange 110 formed on the vertical arm 111 of the pawl 84. Rotation of the member 100 in a counter-clockwise direction, as viewed in Fig. 5, through the medium of the inside knob 46 or the "key control," causes the arm 108 to engage the flange 110 and rotate the pawl 84 about its pivot in a clockwise direction. In the event that the pin 81 is caught behind the shoulder 86 on the pawl 84, as is the case when the shutter is in its operative position as shown in Fig. 7, the pin 81 is released, permitting the shutter 56 to be returned to its normal position under the action of the spring 79.

The various parts are so constructed and arranged that as the bolt is retracted from the keeper, through the medium of the "coin control," the shoulder 86 on the pawl 84 engages behind the pin 81 before the bolt has been entirely retracted or released. This prevents any possibility of a person opening the door through the medium of the "coin control" without the coin slot 76 in the lock case being maintained closed by the shutter 56 after the knob is released. The upwardly extending projection or arm 108 of the member 100 also engages the flange 110 on the downwardly extending arm 111 of the pawl 84 before the bolt has been entirely withdrawn from the keeper through the medium of the inside handle 46, which assures the closure member 56 being returned to its original position upon the room being vacated.

In order that the door to which the lock is applied may be opened from the outside by an attendant or other authorized person without the deposit of a check or coin, provision is made for rotating the member 100 and, in turn, the levers 105 and 108 from the outside of the door through the medium of a "key control." As shown, this "key control" comprises a cylindrical member 114 slidably and rotatably supported in a suitable counterbore 115 in the outside knob 45. Opposite ends of the member 114 are reduced and square in cross-section. The outer square end 116 is adapted to receive a suitable "key" formed on the order of a socket wrench, and the inner square end 117 is adapted to fit into a square hole or socket 118 formed in the end of the member 100. The member 114 is normally retained in a retracted position, that is, in the position shown in Fig. 2, by a spring 120 interposed between the lock case A and a shoulder on the member 114 formed by the reduced portion 117 thereof. The square end 117 is adapted to be projected into

the square aperture 118 formed in the member 100 and the member 100 rotated thereby independently of the outside knob through the medium of a suitable key. As previously pointed out, rotation of the member 100 in a clockwise direction as viewed in Fig. 1 will withdraw the bolt C and "reset" the shutter member 56 in the event the latter is in its closed position. The tongue and groove connection between the shaft 93 and the member 100 permits the lock case and the mechanism assembled therewith to be removed as a unit without disturbing the back plate and the inside knob.

It is thought that the operation of the device will be apparent from the foregoing description thereof. Suffice it to say that a coin or check X of suitable denomination or character inserted through the coin slot 76 in the lock case will be retained in operative position in the coin carrier between the seat 54 formed on the lever 51, and the lower end of the member 50 until the bolt is withdrawn by one of the means provided other than through the medium of the "coin control." This assures the person desiring entrance to the room access thereto upon turning the outside knob a sufficient amount irrespective of how the outside knob is manipulated. As previously stated, the position of the pin 81 relative to the catch 88 on the pawl 84 is such that the shutter member 56, or rather the pin 81 carried thereby, is caught by the pawl before the bolt has been entirely withdrawn from the keeper so as to prevent any possibility of a person entering the room while leaving the lock in condition for the reception of a second coin. The distance between the seat 54 on the lever 51 and the lower end of the member 50 is preferably such that a check of improper character or a coin of incorrect denomination will not be retained therebetween but will drop through the coin carrier into the receptacle at the base of the lock case without permitting actuation of the lock.

As previously stated, one of the objects of the present invention is to provide a lock which is readily applicable to either right or left hand doors, and, for this purpose, the various parts are made reversible or symmetrical. As referred to above, the bolt assembly comprising the bolt C, the member 35, the plate 37, etc., can be reversed by merely changing the aperture through which the bolt projects to the opposite side of the case. The coin carrier can be reversed by merely changing the member 50, the lever 51, and the spring 70 to the opposite sides. Suitable apertures are provided in the various members to make this change possible. For example, the holes for the screws 49 and 52 are duplicated on opposite sides of the center line and the projection 71 on the plate 72 is duplicated on opposite ends of the plate. The duplicate parts are designated by the same reference characters but with a prime mark affixed thereto.

The pawl 84 is preferably manufactured flat and the flange 110 thereon bent one way or the other at the time of assembly, depending upon whether it is to be used in a left hand lock as shown or in a right hand lock. In the case of a right hand lock, the arm 109 on the member 100 engages the flange on the pawl 84 to "reset" the shutter 56 in a manner similar to that in which the arm 108 cooperates with the flange 110 in the left hand lock shown. In order to reverse the closure or shutter 56, it is merely necessary to move the sleeve 83 and the spring 79 to the other side. The notation "in use" appears at op-

posite sides of the word "open," from which it follows that the notation "in use" appears in the slot 92 of the lock case irrespective of whether the shutter moves to the right, as viewed in Fig. 1, for a left hand lock, or to the left as would be the case with a right hand lock.

The present lock is also readily applicable to installations having thick door jambs as well as those with thin jambs. Such an installation is shown in Figs. 10 and 11 in which the parts herefore referred to are designated by the same reference characters. In this event, the keeper proper, in other words, the member 16, is removed from its supporting member 25 and attached directly to the face of the door jamb 150. In the event a vertical molding, such as the molding 121, is employed, as is usually the case, the molding is merely cut out to fit the keeper 16. Preferably, there are employed angular clips or members 122, which shield the rubber stops or bumpers and help to hold the same in place. Each of these clips 122 has a flange 123 thereon adapted to project underneath the adjacent end of the molding. The clips 122 are held in position by screws 125 extending through suitable apertures formed in the flanges 123. The member 16 is secured to the door jamb 150 by screws 126.

Figs. 12 and 13 show the lock as applied to a left hand door which opens out. In this event the keeper comprises a member 130 bolted to the outside face of the jamb 131 and a stop 132 secured to the inside face thereof. The keeper 130 is provided with a rectangular aperture 133 similar to the aperture 20 in the keeper 16, and an inclined surface 134 in front of the slot 133 which serves the usual purpose of retracting the bolt C as the door is closed behind a person entering or leaving the room. The stop 132 includes a rectangular rubber member 135 secured in a suitable groove, which rubber member constitutes the stop proper.

From the foregoing description of the preferred embodiments of my invention it will be apparent that the objects of the invention herefore enumerated have been accomplished, and that there has been provided a simple, reliable, easily assembled lock which cannot be operated by unauthorized persons without the insertion or deposit of a suitable check or coin. The lock is readily applicable to either right or left hand doors and to installations having either thin or thick door jambs. Entrance cannot be obtained by way of the "coin control" without setting the shutter against the insertion of a second coin. In like manner, it is impossible to open the door from the inside without resetting the shutter. The outside knob can be manipulated any number of times and in any manner without releasing the coin or check in the coin carrier so long as the bolt is not retracted independently of the "coin control." The particular shape of the members 50 and 51 shown forms a sinuous path for the coin or check, which together with the particular location of the pivot 52, prevent the possibility of retracting the bolt by means of an instrument inserted through the coin slot at the top of the case.

While the preferred embodiments of the invention have been herein illustrated and described in considerable detail, the invention is not limited to the particular construction shown. Numerous changes in the construction shown, all within the scope of the invention, will suggest themselves to those skilled in the art to which the invention relates, such changes including the use of a

coin tray in the bottom of the lock case for the reception of the coins deposited, changing the lever 51 or the seat 54 to accommodate coins of different denomination and checks of different character, substituting a conventional tumbler lock in the "key control" for the particular device shown, etc. It is my intention to cover hereby all adaptations, modifications, and alternative constructions falling within the spirit and scope of the present invention as defined by the following claims.

I claim:

1. In a coin or check controlled device of the character referred to, the combination of a housing having a slot for the reception of a coin or check, a bolt slidably supported in said housing and normally projecting therefrom, means for continuously urging said bolt in a direction to project the same from said housing, means for retracting said bolt, said means including a coin or check carrier rotatably supported in said housing, means for rotating said coin or check carrier from without said housing, a member pivotally supported by said coin or check carrier, means operatively connecting said member with said bolt for limiting movement of said member relative to said bolt in a direction to retract said bolt, said member being normally retained by said bolt in a position to retain a coin or check in said coin or check carrier in position to limit movement of said member about its pivot relative to said coin or check carrier in the direction in which said first-named means acts thereon upon rotation of said coin or check carrier, and means for retracting said bolt independently of said coin or check carrier whereupon said member is not retained by said bolt in said position to retain a coin or check in said coin or check carrier.

2. In a coin or check controlled device of the character referred to, the combination of a housing having a slot for the reception of a coin or check, a bolt slidably supported in said housing and normally projecting therefrom, means for continuously urging said bolt in a direction to project the same from said housing, means for retracting said bolt, said means comprising a coin or check carrier rotatably supported within said housing, means for rotating said coin or check carrier from without said housing, a member pivotally supported by said coin or check carrier and forming therewith a slot through which a coin or check inserted through said slot in said housing is adapted to travel, means operatively connecting said member with said bolt for limiting movement of said member relative to said bolt in a direction to retract said bolt, said member being normally retained by said bolt in a position to retain a coin or check in said coin or check carrier in position to limit movement of said member about its pivot relative to said coin or check carrier in the direction in which said first-named means acts thereon upon rotation of said coin or check carrier, and means for retracting said bolt independently of said coin or check carrier whereupon said member is not retained by said bolt in said position to retain a coin or check in said coin or check carrier.

3. In a coin or check controlled device of the character referred to, the combination of a housing having a slot for the reception of a coin or check, a bolt slidably supported in said housing and normally projecting therefrom, means continuously urging said bolt in a direction to project the same from said housing, means for re-

tracting said bolt, said means including a coin or check carrier comprising two parallel spaced plates rotatably supported within said housing, means for rotating said coin or check carrier from without said housing, a first member interposed between said plates, a second member interposed between said plates and pivotally supported thereby and forming therewith and with said first-named member a slot through which a coin or check inserted through said slot in said housing is adapted to travel, means operatively connecting the lower end of said second-named member with said bolt for limiting the movement of said second-named member relative to said bolt in a direction to retract said bolt, said second-named member being normally retained by said bolt in a position to retain a coin or check in said slot in said coin or check carrier in position to limit movement of said second-named member about its pivot relative to said coin or check carrier in the direction in which said first-named means acts thereon upon rotation of said coin or check carrier, and means for retracting said bolt independently of said coin or check carrier whereupon said member is not retained by said bolt in said position to retain a coin or check in said coin or check carrier.

4. In a coin or check controlled device of the character referred to, the combination of a housing having a slot for the reception of a coin or check, a shutter member for closing said slot, a bolt slidably supported in said housing and normally projecting therefrom, means continuously urging said bolt in a direction to project the same from said housing, means for retracting said bolt, said means comprising a coin or check carrier rotatably supported within said housing, means for rotating said coin or check carrier within said housing, a member pivotally supported by said coin or check carrier and forming therewith a slot through which a coin or check inserted through said slot in said housing is adapted to travel, means operatively connecting said member with said bolt for limiting movement of said member relative to said bolt in a direction to retract said bolt, said member being normally retained by said bolt in a position to arrest the movement of a coin or check through said slot in said coin or check carrier and retain the coin or check in position to limit movement of said member about its pivot relative to said coin or check carrier in the direction in which said first-named means acts thereon upon rotation of said coin or check carrier, means operatively connecting said member with said shutter member for moving said shutter member in a direction to

close said slot in said housing upon movement of said member to retract said bolt, means for retaining said shutter member in a position to close said slot in said housing, means for retracting said bolt independently of said coin or check carrier whereupon said member is not retained by said bolt in said position to retain a coin or check in said coin or check carrier, a second means for retracting said bolt independently of said coin or check carrier, and means for rendering said sixth-named means inoperative to retain said shutter in position to close said slot in said housing upon actuation of said last-named means.

5. In a coin or check controlled device of the character referred to, the combination of a housing having a slot for the reception of a coin or check, a shutter member for closing said slot in said housing, a bolt slidably supported in said housing and normally projecting therefrom, resilient means for continuously urging said bolt in a direction to project the same from said housing, means for retracting said bolt, said means including a coin or check carrier rotatably supported within said housing, an outside knob for rotating said coin or check carrier from without said housing, a member pivotally supported by said coin or check carrier and forming therewith a slot through which a coin or check inserted through said slot in said housing is adapted to travel, means operatively connecting said member with said bolt for limiting movement of said member relative to said bolt in a direction to retract said bolt, said member being normally retained by said bolt in a position to retain a coin or check of predetermined character inserted through said slot in said coin or check carrier in position to limit movement of said member about its pivot relative to said coin or check carrier in the direction in which said resilient means acts thereon upon rotation of said coin or check carrier, means operatively connecting said member with said shutter member for moving said shutter member into a position to close said slot in said housing upon movement of said member to retract said bolt, a detent or pawl for retaining said shutter member in closed position, means for retracting said bolt independently of said coin or check carrier whereupon said member is not retained by said bolt in said position to retain a coin or check in said coin or check carrier, an inside knob for retracting said bolt, and means for actuating said detent or pawl to release said shutter member upon actuation of said inside knob in a direction to retract said bolt.

CLAUDE R. THOMAS.
